UNITED STATES PATENT OFFICE.

EDWARD L. McCABE, OF CHICAGO, ILLINOIS, ASSIGNOR, BY DIRECT AND MESNE ASSIGNMENTS, TO LINN-McCABE COMPANY, A CORPORATION OF ILLINOIS.

SANITARY DRINKING MECHANISM.

1,083,453.

Specification of Letters Patent.

Patented Jan. 6, 1914.

Application filed October 19, 1911. Serial No. 655,515.

To all whom it may concern:

Be it known that I, EDWARD L. McCABE, a citizen of the United States, residing at Chicago, in the county of Cook and State of Illinois, have invented certain new and useful Improvements in Sanitary Drinking Mechanism; and I do hereby declare the following to be a full, clear, and exact description of the same, reference being had to the accompanying drawings, forming part of this specification, and to the figures and letters of reference marked thereon.

The object of the present invention is to provide a means whereby sanitary drinking fountains may be practically combined and used in connection with an ordinary pump and domestic well such as are commonly found in rural districts, the invention being more especially adapted for use where numbers of persons are in the habit of drinking at the pump or well, for instance, in rural school house yards, etc.

The advantages of, and, in fact at this day, almost necessary for employing sanitary drinking fountains, are well recognized, and in many of the States of the Union laws have been enacted forbidding the use of common drinking cups for general public use, either at school houses or elsewhere, thus requiring individuals to carry their own drinking cups or that means shall be provided whereby the general public may drink without liability of spreading communicable diseases. The sanitary drinking fountain has practically solved the problem wherever a pressure system of drinking water has been installed, but up to this time no solution of the difficulty has been offered where the drinking water is derived from an ordinary well by means of the usual pump for raising water from the well.

In accordance with the present invention provision is made whereby the pump may be utilized to force the water into a small pressure tank against a head of compressed air, and the pressure thus created is utilized to force the water vertically from the nozzle or bubbling valve of the drinking cup, the discharge of water, being, however, controlled by a suitable self-closing valve, whereby the supply is conserved.

Referring to the accompanying drawings,—Figure 1 is an elevation of a pump and sanitary fountain mechanism embody-

ing the present improvements, the well being shown diagrammatically as though in section; and Fig. 2 is a detail section on an enlarged scale of a preferred form of self-closing valve for controlling the discharge of water from the tank through the bubbling valve of the fountain.

In said drawings the letter A indicates a force pump of ordinary construction having a valved discharge spout B and a depending well pipe or tube C with the usual cylinder C' containing a piston adapted to be operated by the pump handle A' for lifting the water from the well and discharging it through the spout B. In accordance with the present invention there is hung at one side of the well pipe C and preferably on brackets D a vertically arranged tank E. The tank E has a capacity commensurate with the demands to be made upon the apparatus, and at the bottom it is connected through a pipe F with the well pipe C at a point above the cylinder C'. In the pipe F there is included a check valve indicated at F' whereby water forced from the pipe C through the pipe F into the bottom of the tank E is held against reverse movement, or, in other words, it will be forced into and held by the tank E against the air pressure therein. From the bottom of the tank E, a pipe G leads up through the well platform H and terminates in a bubbling valve or cup I, preferably located in the usual basin K which serves to carry off the waste. In the pipe G there is interposed a self-closing valve L, and inasmuch as in the present device it is desirable that no water should be allowed to stand in any pipe or part exposed above the platform where it may freeze, the valve L is located at the lower end or portion of the pipe G, and in addition to controlling the flow of water from the tank E to the cup or bubbling valve I, it is provided with a drip opening L', through which the discharge end of the pipe G will be emptied when the valve L is closed. For operating the valve L a long valve stem M extends up above the platform H and into convenient position for being operated in the ordinary way, the said valve is preferably invariably of the self-closing type and is shown with a closing spring L' in Fig. 2.

The tank E is at the upper end provided with a removable plug e and at its lower

end with a drain cock e' , whereby it may be emptied and air admitted at the upper end, this being a convenient provision for insuring the sufficient body of air within the tank to give the desired pressure and to effectually discharge practically all of the water from the tank before requiring the pump to be operated to supply more water.

In operation it is obvious that by closing 10 the spout B of the pump and operating the handle A' water will be forced into the tank E, thereby compressing the air in the tank, and that by the manipulation of the valve L, the water may be drawn off through the 15 bubbling valve or jet by any one who desires to obtain a drink.

The whole apparatus is of such form and construction that it may be readily installed 20 in connection with an ordinary pump and it is preferably so arranged that the tank E, together with the lower portion of the pipe G and valve stem M are all mounted in a definite relation to each other in the brackets D and the brackets D are provided with 25 eyes d through which the well pipe C may be passed and the whole supported by collars d' secured to the well pipe C by set screws or other ordinary fastening means.

Having thus described my invention what 30 I claim as new and desire to secure by Letters Patent of the United States, is:

1. In an apparatus such as described, the combination with a force pump having a depending well pipe, laterally extending

brackets on said well pipe, a pressure tank 35 carried by said brackets and in communication at its lower end with the well pipe, a check valve interposed between the pipe and tank, a discharge pipe leading from the bottom of the tank, upwardly to a point in 40 proximity to the pump, a bubbling cup located at the upper end of said discharge pipe, and a valve in said discharge pipe near its lower end with means for operating said valve extending up into proximity to 45 the bubbling cup.

2. In an apparatus such as described, the combination with a force pump having a depending well pipe, a bracket connected with said well pipe, a pressure tank mounted on the bracket and at its lower end in communication with the well pipe, a check valve interposed between the well pipe and tank, a discharge pipe leading from the lower end of the tank to a point above the 50 tank, a bubbling cup at the upper end of said discharge pipe, a valve controlling said discharge pipe and having means in proximity to the bubbling cup whereby it may be opened, a drain cock at the bottom of the 55 tank, an air inlet opening at the top of the tank, and means whereby said air inlet opening may be closed, substantially as described.

EDWARD L. McCABE.
